UNITED STATES PATENT OFFICE.

THEODORE H. JOSEPH AND JAMES J. EHRENREICH, OF NEW YORK, N. Y.

ELECTRICALLY-DRIVEN MACHINE.

SPECIFICATION forming part of Letters Patent No. 655,491, dated August 7, 1900.

Application filed January 27, 1899. Serial No. 703,554. (No model.)

To all whom it may concern:

Be it known that we, THEODORE H. JOSEPH and JAMES J. EHRENREICH, citizens of the United States of America, and residents of 5 New York city, in the county and State of New York, have invented a new and useful Improvement in Electrically-Driven Machines, of which the following is a specification.

Our invention relates to means for electrically driving small machines, like sewing-machines, in such a manner that the operator may control the motor and the brake by the foot or feet, while the hands are left free to 15 attend to the product being worked upon by the machine.

The organization embodying our invention consists of the combination of a compound pedal, the one part serving to start the motor 20 by turning on the electric current through a rheostat and to release the brake from the driving-pulley of the motor, and the other part serving the purpose of releasing the first part, and thus applying the brake and turning 25 off the current. A ratchet on the one part of the compound pedal automatically holds the main pedal at any desired position to regulate the current, and hence the speed 30 of the motor. By pressing the foot on the pedal which is connected to the ratchet the latter is released from the main pedal, which rises and applies the brake and turns off the current simultaneously approximately.

We have constructed the device in such a 35 manner that it may be applied to any of the ordinary sewing-machines.

Referring to the accompanying drawings, Figure 1 shows a plan of the whole combination, the outer dotted lines representing the 40 outline of the table for supporting the machine, such as a sewing-machine, and the inner dotted rectangle representing the outline of the base of the sewing-machine itself. The view is the same as if the said table were 45 transparent, our apparatus being located under the table. In order to get the whole within the limits of the sheet of drawings, the parts of the device are on a rather small scale, but the details are mostly shown in other 50 figures by themselves on a much larger scale. The phase of the mechanisms in this figure is that of the normal condition. Fig. 2 is a

view similar to that in Fig. 1, except that the same is a side elevation, that the phase is that in which the current is turned on full 55 and the brake is released, and that the handle *d* is on the opposite side of the rheostat *c*. Fig. 3 is a view similar to that shown in Figs. 2 and 1, except that the same is an end elevation of the essential elements in so far as 60 they do not cause confusion, some of the rear parts being omitted. The phase is normal, ready for starting. Fig. 4 is an enlarged view of the brake by itself, showing it pivoted to a block. Fig. 5 is an enlarged view of the 65 stopping-pedal, showing also the spring. The device is in section, partly. Fig. 6 is a different view of that which is shown in Fig. 4. Fig. 7 is a half of one of the bearings of the stopping-pedal, showing especially the 70 lug for holding one end of the spring. Fig. 8 is a side view of part of the main or starting pedal, shown hinged at one end to a support. Fig. 9 is a side view, and Fig. 10 a section, at a different angle of the crank for 75 applying the brake. Fig. 11 is the connecting-rod for joining the handle of the rheostat to the said crank for purposes hereinafter stated.

a is the motor for driving the sewing-machine, and *b* is its pulley, grooved to receive the usual driving cord or belt.

c is the rheostat for turning on and regulating the current for propelling the motor *a*, and *d* is its handle. When the handle *d* is 85 turned to the left, the current is increased and when turned to the right it is diminished.

e is a chain connecting the handle *d* over the pulley *f* to the free end of the starting-pedal *g*, the other end being hinged by a hinge 90 *h* to the foundation *i*. A spring *j* is connected to the handle to resist the action of the pedal *g*, the other end of the spring being connected to the post *k*. A ratchet *l* is so located that its teeth may catch the pedal *g* as it is pushed 95 downward, being pivoted upon the bearings *m*, so as to turn to and from the pedal *g*, the spring *n* bearing against the ratchet to hold the latter against the pedal. The ratchet carries at right angles to the same a stopping- 100 pedal *o*, which on being pressed overcomes the action of the spring and releases the pedal *g* from the said ratchet. One end of the spring *n* bears against the back of the ratchet,

as stated, and the other end bears against the lug p , which is mounted upon the bearing m , the spring coiling around the shaft q of the ratchet l . The brake r is also connected up with the handle d of the rheostat, the said brake r being pivoted by the pin s to the block s' , which is stationary. The brake is carried upon a fork t , the tines t' spreading to opposite sides of the block s' . Normally the brake r is held away from the pulley b by a spring u , which is fixed at one end by staples u' . The spring u is also forked, so that the respective tines may press upon the tines of the fork t , which carries the brake r . Normally the finger v on the rod v' bears against and holds the brake r against the pulley b through the action of the crank v'' , which is connected to the handle d of the rheostat and to the spring j by the connecting-rod w . The rod v' is adapted to rotate on its own axis in view of the bearings x , which are attached to the under side of the table y , which is shown in Figs. 2 and 3. The form of connection between the crank v'' and the rod w is a hook-joint, the hook w' being on the end of the rod w and the rod w being adapted to slide along and over the crank, so that the latter will be operated by one motion of the rod w and not by the other or opposite motion. In Fig. 1 the hook is retaining the crank, and hence the brake is in a fixed position, while in Fig. 2 the hook is shown as removed to the left, by which means the crank v'' has been turned to the left and the finger v has turned over through an angle and released the brake r from the pulley b . To permit of adjustment, the rod w is made in two parts, which are connected by a screw-clamp w'' . As the handle d carries a current, the same is insulated from the rod w and from the spring j and chain e by means of insulation z . We will now describe the *modus operandi* of our invention.

To start the machine or motor a , having the driving-pulley b , the starting-pedal g is pressed downward by the operator's foot until by the sound or otherwise she knows that the machine is running at the desired speed. The ratchet l catches and holds the pedal g , and hence the handle d of the rheostat, at approximately the proper position to maintain this speed, and the operator's foot may be removed, so as to be ready to stop the operation by pressing upon the other pedal o . The pressure of the pedal g pulls upon the chain e , which pulls upon the handle d , and the spring j is extended, as seen in Fig. 2, and thereby put under tension. The movement of the handle d to the left by the said action of the pedal g throws the hook w' to the left to free the crank v'' , and consequently the spring u presses the brake r upward, which turns the finger t upward and turns the crank v'' downward, ready to be again acted upon by the hook near its finish when

the handle d turns back to its normal position, which happens by pressing with the foot upon the stopping-pedal o . This last action releases the pedal g from the ratchet l , and the spring j pulls the pedal upward and pulls the handle d and rod w , for the purposes already stated. These operations may be repeated indefinitely.

We claim as our invention—

1. The combination with a machine to be driven by a motor, of a brake for the motor, a rheostat for regulating the current of the motor, a starting-pedal connected up with both the said brake and said rheostat, and a retractile spring for returning the pedal, rheostat and brake to their normal phases, and means for causing the said brake to be non-active, permanently, said means consisting of a rod adjustable in length forming a connecting-rod between the said brake and the said rheostat. 75

2. The combination with a machine to be driven by a motor, of a brake, a rheostat for respectively stopping and operating the motor in the usual manner, a pedal for operating the rheostat against the action of a retractile spring, and means for applying and releasing the said brake actuated by said rheostat mechanically, said means consisting of a crank for applying the brake against the action of a retractile spring, and a rod, adjustable in length, connecting said rheostat to said crank. 90

3. The combination with a machine to be driven, of a motor, a rheostat for regulating the current for the motor, a brake for stopping the pulley of the motor, a starting-pedal, a chain connecting the pedal to the handle of the rheostat, a spring j acting as a retractile spring to return the said handle to its original position, a crank provided with a finger which bears upon the brake to apply it against the action of a spring u , a connecting-rod, having a hook, engaging with the said crank, and adapted to actuate said crank at one portion of its throw only, the second spring u , being for returning the brake from pressing upon the said pulley, and a second or stopping pedal, having a ratchet to hold the starting-pedal in different positions, and adapted to release the said starting-pedal, and means for adjusting the length of said connecting-rod. 105

4. The combination, with a motor for driving a machine, of a rheostat for regulating the current for the motor, a brake for stopping the pulley of the motor, a pedal, a chain connecting the pedal to the handle of the rheostat, a spring j , acting as a retractile spring to return the said handle and the said pedal to their original positions, a crank provided with a finger which bears upon the brake, to apply it against the action of a given spring u , a connecting-rod having a hook, which engages with said crank, and adapted to actuate said crank at one portion 120

of its throw only, the second spring u , being for returning the brake from pressing upon said pulley.

5. The combination, with the table of a machine, of a rheostat secured on the under side thereof, and having a handle, a retractile spring, having one end secured to said handle, and the other to a post k projecting downward from the said table, a rod extending from the said handle, parallel to the under surface of the table, a second rod v' having a crank at one end, and a finger at the other, and lying parallel to the said surface, and at an angle to the first rod, which is provided with a hook, which engages with the said crank, a motor secured under the

table, with its driving-pulley located beneath the said finger, a brake for said pulley, a spring u , normally tending to hold the brake away from the said pulley, said brake being 20 normally held against the pulley against the action of the spring u , and cleats for holding the rod v' to the under side of the table.

In testimony whereof we have hereunto subscribed our names this 25th day of January, 25 1899.
